(57) **CLAIM**

The ornamental design for a grille for a ceiling ventilating fan, as shown and described.

DESCRIPTION

FIG. 1 is a perspective view of the top, front and left side of a grille for a ceiling ventilating fan showing our new design;

FIG. 2 is a front view thereof;

FIG. 3 is a left side view thereof;

FIG. 4 is a right side view thereof;

FIG. 5 is a top plan view thereof;

FIG. 6 is a bottom view thereof; and,

FIG. 7 is a rear view thereof.

The broken line showing of portions of the grill is for the purpose of illustrating environmental structure and forms no part of the claimed design.
